UNITED STATES PATENT OFFICE.

JOHN P. CASEY, OF FLEMINGTON, NEW JERSEY.

DESIGN FOR A COMBINED SUGAR AND CREAMER.

48,540.

Specification for Design.

Patented Feb. 8, 1916.

Application filed September 3, 1915. Serial No. 48,891. Term of patent 14 years.

To all whom it may concern:

Be it known that I, JOHN P. CASEY, a citizen of the United States, residing at Flemington, in the county of Hunterdon and State of New Jersey, have invented a new, original, and ornamental Design for a Combined Sugar and Creamer, of which the following is a specification, reference being had to the accompanying drawing, forming part thereof.

The figure is a perspective view of the combined sugar and creamer.

I claim:

The ornamental design for a combined sugar and creamer, as shown.

Witnesses:

M. E. LAUGHLIN,
GEO. F. BYRNE.
